Primary Examiner—Philip S. Hyder(74) *Attorney, Agent, or Firm*—John R. Lansdowne(57) **CLAIM**

The ornamental design for a musician's stage box, as shown and described.

DESCRIPTION

FIG. 1 is a perspective view of a musician's stage box showing my new design, with the top and bottom covers removed and a sliding tray in the bottom compartment extended;

FIG. 2 top plan view thereof;

FIG. 3 is a bottom plan view thereof;

FIG. 4 is a front elevation view thereof;

FIG. 5 is a rear elevation view thereof;

FIG. 6 is a right side elevation view thereof;

FIG. 7 is a left side elevation view thereof; and,

FIG. 8 is a perspective view thereof, with said top and bottom covers in place and said tray retracted.

The broken line portions of the disclosure are for illustrative purposes only and form no part of the claimed design.
